UNITED STATES PATENT OFFICE.

HERMANN ALMAKER, OF NEW YORK, N. Y.

DESIGN FOR A COLLAR.

45,611.

Specification for Design.

Patented Apr. 21, 1914.

Application filed February 27, 1914. Serial No. 821,585. Term of patent 7 years.

To all whom it may concern:

Be it known that I, HERMANN ALMAKER, a subject of the Emperor of Germany, and residing in the borough of Bronx, city of New York, in the county of Bronx, State of New York, have invented a new, original, and ornamental Design for a Collar, of which the following is a specification, reference being had to the accompanying drawing, forming part thereof.

The figure is a perspective view of my newly designed collar.

I claim:

The ornamental design for a collar, as shown.

HERMANN ALMAKER.

Witnesses:

C. MULREANY,
S. ANDREWS.
